UNITED STATES PATENT OFFICE.

MARK A. POWERS, OF DALLAS, TEXAS.

DESIGN FOR A COMBINED BEVERAGE COOLER AND DISPENSER.

Application filed April 29, 1927. Serial No. 21,787. Term of patent 7 years.

To all whom it may concern:

Be it known that I, MARK A. POWERS, a citizen of the United States, residing at Dallas, in the county of Dallas and State of Texas, have invented a new, original, and ornamental Design for a Combined Beverage Cooler and Dispenser, of which the following is a specification, reference being had to the accompanying drawing, forming part thereof.

The figure is an isometric perspective view of the article showing my design.

I claim:

The ornamental design for a combined beverage cooler and dispenser, as shown.

MARK A. POWERS.
